UNITED STATES PATENT OFFICE.

HARRY T. CRANE, OF CINCINNATI, OHIO.

COMBINED BLOTTER, CALENDAR, RULER, MEASURE, AND PAPER-CUTTER.

No. 891,819.

Specification of Letters Patent. Patented June 30, 1908.

Application filed September 22, 1906. Serial No. 335,693.

To all whom it may concern:

Be it known that I, HARRY T. CRANE, a citizen of the United States, and a resident of the city of Cincinnati, in the county of Hamilton and State of Ohio, have invented certain new and useful Improvements in a Combination Blotter, Calendar, Ruler, Measure, and Paper-Cutter, of which the following is a specification.

10 The several features of my invention and the various advantages resulting from their use conjointly or otherwise will be apparent from the following description and claims.

In the accompanying drawings, making a 15 part of this application, and in which similar letters of reference indicate corresponding parts,—Figure 1 is a top view (or front elevation) of an article embodying my invention. Fig. 2 represents a vertical transverse section 20 of the article taken in the plane of the dotted line 2, 2, of Fig. 1. Fig. 3 is a plan view of a modification of the ruler illustrated in Figs. 1 and 2, and here shown separated from the remainder of the article represented in said

25 Figs. 1 and 2. Fig. 4 is a vertical transverse section of a modification of the ruler shown in Fig. 3. This section is in the plane of the dotted line 4, 4, of Fig. 3. Fig. 5 is a vertical transverse section of the article shown in Fig. 30 1, in a case where the superincumbent layer of transparent celluloid extends from the edge of the ruler down over the article as far as the dotted line X, X, of Fig. 1, and stops at this line.

35 I will now proceed to describe my invention in detail.

A indicates the article. This article consists as follows: I provide a front record plate or piece B, made of paper, or similar 40 material. On one portion of this piece B are printed or otherwise marked the graduations of a measure B². In this measure the graduations may be made of one kind or another, but a desirable measure is that of the inch, 45 and fractions of the same. The present illustrative specimen shows a six inch measure. I combine with this a ruler, consisting of the straight edge B³. I cover this straight edge B³ with a film of stiff transparent celluloid 50 B⁴, and extend this celluloid over the graduations of the measure B². The mode of applying this celluloid is by bending a broad marginal portion, at B⁵, around and under the straight edge as shown in Fig. 2. I also 55 mark upon this plate B, a calendar B⁶, and preferably arrange the months (with their

days numbered) on the left hand margin and on the right hand margin and along the lower margin. I reserve the central space B⁷, bounded by the measure and the calendar, 60 for the insertion of a trade-mark, an owner's name, a proprietary name, a notice, or an advertisement, as the case may be. I locate beneath this plate B a desired number of sheets B⁸ of blotting paper, preferably twelve 65 sheets when the blotting paper is thin. In the drawing, Fig. 2, I have shown three of such sheets B⁸,—premising that the number of sheets is to be varied according to the taste and wish of the manufacturer. I connect 70 these sheets together at their margins and to the plate B at its margin. This article is not only useful as a calendar, but it is useful as a measure, and as an advertising medium. It is also exceedingly useful as a measure, 75 and especially as a straight edge ruler.

The transparent celluloid covers preferably the entire face of the card. This celluloid is perfectly transparent, so that all the printing, lettering, words, figures and 80 marks can be readily seen beneath it. The celluloid film B⁴ protects the plate B from dust and dirt. Any dirt or smooch which gathers on the celluloid can be quickly and readily sponged off or otherwise removed. 85

The marginal bend B⁵ of the celluloid film, at and around the straight edge makes a very efficient straight edge by which ruling can be done. This edge is hard, smooth and durable. The pencil or drawing pen slips along it (this edge) without interruption. This edge can be readily cleaned. The celluloid being transparent, permits the graduations of the measure at this edge to be seen perfectly. I have, 95 therefore, a measure and a straight edge of exceptional value.

The celluloid film B⁴ which extended over the entire face of the plate B, is preferably secured in place at that edge of the plate B 100 which is opposite the measure and straight edge B³, by bending it over at B⁵ and under the plate B. After having been once bent to form, by the proper means, the celluloid will retain the bends, and will closely embrace the plate B, so that even where the celluloid is not otherwise connected to the plate, either by adhesive substances, or mechanical means, as rivets or clamps, it 105 will not be easy to remove it from the plate B.

The blotting pads are preferably secured

to the plate B and to the adjacent under side of the margin of the celluloid by an adhesive substance. The celluloid can, if desired, be secured to the plate B, not only by the bends B⁵, B⁹, but also by adhesive substances or mechanical means.

In use, the blotting paper sheets as they become soiled, are successively removed, by tearing them off. After they are all removed, the plate with its calendars and straight edge and measure will still remain of great value.

When desired, the celluloid film may cover the straight edge and the measure, and may extend as far as the dotted line X, X, of Fig. 1, and stop there and the remainder of the plate from said line X, X, to the edge B⁹ be without a covering of the celluloid film. See Figs. 1 and 5. In such construction, the celluloid may be secured at its edge along the dotted line X, X, or at the ends by an adhesive substance, or other means. But the above modification I regard as an inferior one.

The measure and straight edge covered with celluloid is a valuable article. When used together and without a calendar, or an extended plate B, the construction is preferably that shown in Figs. 3 and 4. In this construction, a plate C (of course narrow) is present. On the plate C is marked the measure C². A space C¹⁰ below the measure affords a place for any memorandum, name, advertisement, etc. The celluloid C⁴ is, at the lower edge C¹² of this measure, preferably bent around this edge and back under the plate C, as illustrated in Fig. 4, at C⁵. Under this celluloid and under the plate C, I prefer to place a thick pad C¹³ of blotting paper, preferably in one piece. This pad is not so valuable as a blotter, because the measure is narrow, but is of great service in preventing the measure and the straight edge C³ from slipping out of or away from the location in which it is placed, in order to measure a certain distance, or to rule a line at a given place.

On all of these devices heretofore specified, the celluloid confers cleanliness and durability. The ruling on the straight edge can be made with ease, by reason of the smooth celluloid, and by the pad below the ruler is held firmly in the desired position without much, if any, pressure on the ruler.

My invention enables the devices herein set forth to be used for cutting, that is, tearing paper in a straight line. Such use will be readily understood.

Although celluloid is the preferred substance for covering the straight edge and the measure, or the whole of the face of the top, I wish it to be understood that other transparent substances such as gelatin, enamel and the like may be employed instead.

Of course where there was no celluloid to be employed, there need be no other transparent substance employed.

While celluloid is the preferred covering for the straight edge, yet aluminum or other metal might be used, but I prefer to employ celluloid. The celluloid or the like might curl up and over the edge of the pad, instead of being bent over, down and under. This would be obviously a modification of my invention.

Where the words "printed matter" are used in the claims, it is understood to include not only words, but lettering, figures, marks and designs.

What I claim as new, and of my invention and desire to secure by Letters Patent, is:—

1. A combined instrument, composed of a plate, on which a place is left upon which a measure may be marked, and having a space for the insertion thereon of printed matter, the plate being covered with a transparent film of celluloid bent around one edge, and there forming a straight edge, a blotting pad being affixed to the under side of the plate, substantially as and for the purposes specified.

2. A combination instrument, composed of a plate on which a place is left upon which a measure may be marked, and having a space near the measure on which printed or illustrated matter may be inserted, a film of celluloid, bent over one edge of the plate, and extended over the plate, and a blotting pad, or base, affixed to the under side of said plate, substantially as and for the purposes specified.

3. In a combination instrument, a plate containing a place on which a measure may be marked, and straight edge, and covered with a film of celluloid whose edge is bent around and under the straight edge, substantially as and for the purposes specified.

4. In a combination instrument, a plate containing a place on which a measure may be marked, and straight edge, and covered with a film of celluloid whose edge is bent around and under the straight edge, and a basal pad onto which the plate with celluloid is attached, substantially as and for the purposes specified.

5. A combined instrument, composed of a plate, on which a place is left upon which a measure may be marked, and having a space for the insertion thereon of printed matter, the plate being covered with a transparent film of celluloid bent around one edge, and there forming a straight edge, substantially as and for the purposes specified.

6. A combined instrument composed of the plate on which a place is left upon which a measure may be marked, and having the space for the insertion thereon of printed matter, one edge of the plate formed as a

straight edge, a blotting pad fixed to the under side of the plate, substantially as and for the purposes specified.

7. A combination instrument on which a place is left upon which a measure may be marked and having a space near the first named place on which printed or illustrated matter may be inserted, one of the edges of the plate being formed as a straight edge, 15 and a blotting pad fixed to the under side of the plate, substantially as and for the purposes specified.

8. A combination instrument on which a

place is left upon which a measure may be marked and having a space near the first 15 named place on which printed or illustrated matter may be inserted, one of the edges of the plate being formed as a straight edge, this edge being protected by a stiff reinforcement, substantially as and for the purposes 20 specified.

HARRY T. CRANE.
